UNITED STATES PATENT OFFICE

EVERETT S. GREER, OF ZANESVILLE, OHIO, ASSIGNOR TO HAZEL-ATLAS GLASS CO., OF WHEELING, WEST VIRGINIA, A CORPORATION OF WEST VIRGINIA

GLASS-FEEDING MECHANISM

Application filed March 3, 1927. Serial No. 172,352.

The invention relates generally to means for automatically feeding formed charges of glass to fabricating machines, and in particular, the invention involves new and improved means for more accurately controlling the size, weight and shape of the glass charges.

The various novel features of construction and operation, and the advantages thereof, will be apparent to those skilled in the art, from the following detailed description when taken in connection with the accompanying drawings; in which

Figure 1 is a vertical sectional view of the feeder, mounted in a conventional flow spout; and

Figure 2 is a front elevational view of the feeder and flow spout.

Referring to the drawings more in detail, numeral 1 indicates the conventional flow spout which extends from the glass tank in the usual manner; the flow spout being provided with the ordinary flow orifice 2, and also provided with the ordinary burners (not shown).

In accordance with the usual practice the flow orifice is provided with a variable size bushing 3, through which the glass is delivered to forming machines for the fabrication of glass articles of various forms, weights and sizes. It has been the common practice in the glass art for many years to control the shape, weight and size of these glass charges in accordance with the shape, weight and size of the articles to be fabricated; but the present invention involves an improved mechanism for more accurately controlling the above-mentioned characteristics of the glass charges. While it is old, as mentioned above, to employ bushings in the flow spout, I have discovered that by employing a bushing which projects upwardly above the floor of the flow spout, and vertically adjusting the bushing so as to alter the upper end 4 of the bushing with respect to the glass level, that it becomes possible to regulate and control to a very fine degree, the shape, weight and size of the glass charges; thereby providing a more sensitive

control of these characteristics than has been possible heretofore.

It will be understood, of course, that the invention contemplates the use of any appropriate means for adjusting the bushing 3 to secure the desired head of glass; and therefore, the particular means now to be described will be considered merely as illustrative.

A lever 5 is pivotally mounted intermediate its ends, as indicated by numeral 6, and one end of this lever is provided with a fork 7; the tines of the fork having open ended slots 7'. These slots receive trunnions 8 provided on the split ring 8' which is clamped in the channel 8'' adjacent the lower end of the bushing 3. The opposite end of the lever 5 is provided with a hole 9 adapted to receive a threaded rod 10, which in the present instance is fixed to the flow spout 11 casing; it being understood that the diameter of the hole is somewhat larger than that of the threaded rod, to permit the pivotal movement of the lever. Adjusting nuts 11, 11', are mounted on the threaded rod above and below the end of the lever 5, thereby providing a very fine vertical adjustment of the bushing 3.

By varying the vertical position of the bushing, thereby varying the head of glass, I am able to obtain a more sensitive control of the shape, size and weight of the glass charges, than has been possible heretofore; and this constitutes one of the material features of the invention.

It has long been the practice in the glass art to vertically reciprocate an element in the glass, in vertical alignment with the flow orifice, to control the flow of glass through the orifice; and one of the material features of the present invention resides in the improvement of the reciprocable element, which will now be described.

Instead of employing the usual needle or plug, I employ a bell-shaped reciprocable member 12, which is of greater internal diameter than the bushing 3, so that it will embrace the bushing but be spaced therefrom. The upper end of the hollow reciprocable member is provided with a passage 13 which

communicates with the atmosphere, whereby the glass within the reciprocable member is always under the influence of atmospheric pressure. The action of a reciprocable plug 5 for controlling the flow of glass is so well known that it is needless to describe such action here; it being sufficient to state that the action of this hollow reciprocable member is similar to that of the well known plug, 10 the main difference being that the present element presents a far greater area to the glass, thereby giving a correspondingly greater control of the glass. And by reason of the interior of the hollow reciprocable member 15 having communication with the atmosphere, the pressure within the member remains constant during the reciprocation of the member.

Any well known or other mechanical expedients 20 may be employed for reciprocating the hollow member and for adjusting the length or limits of the strokes; and the particular means that I have shown, and which will be briefly described hereinafter, will be 25 considered merely as an example of any equivalent means that may be employed.

A bracket 14 embraces the upper end of the hollow reciprocable member 12, and is preferably seated in a circumferential channel 15, while the opposite end of the bracket is removably fixed to the upper end of a piston rod 16. This piston rod carries the usual piston 17 mounted in a fluid pressure cylinder 18 which, in the present instance, is mounted directly on the flow spout casing. The piston and rod, and consequently the hollow feeder member, are reciprocated by the alternate admission of air or other fluid pressure to opposite ends of the cylinder through the 30 usual pipes 19, 19'; the admission and exhaust of the air or other fluid pressure being controlled by the usual valves and timing mechanism (not shown). A simple means for controlling the length and limits of the 35 strokes of the feeder member is provided by the rod 20 which is carried by the piston and extends downwardly through the lower end of the cylinder. The rod 20 extends loosely through an appropriate opening provided in 40 a bracket 21 fixed to the flow spout casing, and nuts 22, 22', are threaded onto the rod above and below the bracket, to adjustably determine the upper and lower limits of stroke.

55 In operation, the hollow feeder member 12 is reciprocated to alternately accelerate and retard the flow of glass through the bushing 3, to thereby form suspended gobs or charges, in the same manner as in the well known reciprocating plug feeder, but this hollow feeder member has a much better control of the glass for the reason that its area in contact with the glass greatly exceeds that of the ordinary reciprocating plug. Variations in the 60 size, shape and weight of the suspended

charges are accomplished, in part, by varying the limits of stroke or the length of stroke, etc., of the feeder member, as in the case of the ordinary reciprocating plug; and the formed charges are severed at the proper time by the shears 23 and drop into the molds of fabricating machines, in accordance with the established practice. In the present feeder, however, the size, weight and shape of the gobs is not only more accurately controlled 70 because of the particular feeder member, but also because of the bushing 3, which extends up into the glass, and by the vertical adjustment of which the head of glass may be varied as desired, thereby providing a hitherto 75 unknown refinement in the control of the size, shape and weight of formed suspended glass charges.

What I claim as new is:

1. A glass feeder including a flow spout 85 having a flow orifice, and a bushing adjustable to vary the head of glass.

2. A glass feeder including a flow spout having a flow orifice, an adjustable bushing arranged in said orifice, and means for controlling the head of glass above said bushing 90 by adjustment of the bushing.

3. A glass feeder including a flow spout having a flow orifice, and a bushing arranged in said orifice, said bushing varying the head 95 of glass by vertical adjustment.

4. A glass feeder including a flow spout having a flow orifice, a bushing arranged in said orifice, said bushing being vertically adjustable to control the size, weight and shape 100 of suspended glass charges.

5. A glass feeder including a flow spout having a flow orifice, and a bushing arranged in said orifice, said bushing being vertically adjustable to vary the head of glass. 105

6. A glass feeder including a flow spout having a flow orifice, a bushing arranged in said orifice and extending above the floor of the flow spout, and a reciprocable feeder member, said feeder member being hollow and of such internal diameter as to embrace said bushing, the interior of said feeder member being always at atmospheric pressure. 110

7. A glass feeder including a flow spout having a flow orifice, a hollow reciprocable feeder member arranged in the flow spout above said orifice, means for reciprocating the hollow feeder member, and a bushing adjustable to vary the head of glass. 115

8. A glass feeder including a flow spout having a flow orifice, a bushing arranged in said orifice, a hollow feeder member arranged in the flow spout above said orifice, means for reciprocating the hollow feeder member, and means for vertically adjusting said bushing. 120

9. A glass feeder including a flow spout having a flow orifice, a bushing arranged within said orifice, a hollow reciprocable feeder member of such internal diameter as 125

130

to embrace the bushing, said bushing being adjustable to vary the head of glass.

10. A glass feeder including a flow spout having a flow orifice, a bushing arranged in said orifice, an implement within the glass and above the orifice for controlling the flow of glass, and means for vertically adjusting said bushing to vary the head of glass.

11. A glass feeder including a flow spout having a flow orifice, a bushing arranged in said orifice, a vertically reciprocating implement within the glass and above the orifice for controlling the flow of glass, and means for vertically adjusting said bushing to vary the head of glass.

15. 12. A glass feeder including a flow spout having a flow orifice, a bushing arranged in said orifice, means for periodically increasing and decreasing the pressure on the glass over the bushing, and means for vertically adjusting the bushing to vary the head of glass.
